LONG-STROKE PUMPING JACK

Application filed October 26, 1929. Serial No. 402,606.

This invention relates to a device for transmitting rotary motion to reciprocating motion, and further relates to a device of this character which may be used as a long stroke pumping jack for reciprocating the pump rods of a deep well pump.

In oil wells reciprocating pumps are often placed at great depths, with the result that the elongation and contraction of the pump rods of the pump play a very important part in the efficiency of the pumping equipment. It is found that to increase the length of stroke of a pump of the type used in pumping oil from wells will reduce the losses resulting 10 in change of length of the pump rods or sucker rods as such parts are reciprocated.

It is an object of my invention to provide a device which will economically and efficiently transfer rotary motion to a long reciprocating motion, it being possible to make the length of the reciprocating stroke of any desired magnitude by merely changing the length of traveler members or chains and repositioning the guide members or sprockets 15 over which these chains travel.

A further object of the invention is to provide a simple form of bracket means for connecting the traveler members or chains to a reciprocating member, such as a string of 20 sucker rods.

A further object of the invention is to provide a simple means for preventing bending or disaligning of the upper end of the polish rod of a string of sucker rods.

Further objects and advantages of the invention will be made evident throughout the following part of the specification.

Referring to the drawings which are for illustrative purposes only,

Fig. 1 is a front elevational view showing a device embodying the present invention.

Fig. 2 is a side elevation corresponding to Fig. 1.

Fig. 3 is a horizontal cross section on a plane represented by the line 3—3 of Fig. 2.

Fig. 4 is a diagrammatic view for demonstrating the operation of the alignment compensating device forming part of the invention.

Fig. 5 is an enlarged partly sectioned de-

tail showing an alternative form of alignment compensating device.

In the embodiment of my invention represented in the drawings I show a frame 11 consisting of vertical posts 12 and 13 which 55 extend upwardly from a base structure 14 and have their upper ends connected together by a cross bar 15. The base member 14 is adapted for mounting on the floor 16 of a derrick in such position that the posts 12 and 13 will be spaced on either side of a pump tubing 17 which projects upwardly from a well casting 18 and through the floor 16 of the derrick, there being a packing head 19 at the upper end of the pump tubing 17 through which a 60 polish rod 20 extends. The posts 12 and 13 are conveniently made from pairs of structural channels 22, as shown best in Figs. 1 and 3, and these posts may be reinforced in upright position relative to the base 14 by brackets 23, it being understood that the details of construction of the frame 11 are not important to the practice of the invention. By means of upper brackets 24 and 25 which 65 project forwardly from the posts 12 and 13, shafts 26 and 27 are held in inwardly projecting positions of axial alignment, as shown in Figs. 1 and 3, and on the inner ends of these shafts 26 and 27 upper sprockets 28 and 29 are mounted. By means of lower brackets 70 75 22 and 33, lower shafts 34 and 35 are held in inwardly extended and axially aligned position, it being preferable to place the lower shafts 34 and 35 in a vertical plane extending through the upper shafts 26 and 27. Mounted on the inner ends of the shafts 70 75 80 34 and 35 are lower sprockets 36 and 37 which are vertically aligned with the respective upper sprockets 28 and 29. Over the right-hand vertically aligned sprockets 28 and 36 a traveler member or chain 40 is carried, and over the left-hand pair of sprockets 29 and 37 a traveler member or chain 41 is carried.

From Fig. 2 it will be noted that the axes 85 90 95 of the sprockets 28 and 29, 36 and 37, and the polish rod 20 all extend in the same vertical plane, and it will be further noted that the front and back vertical portions 42 and 43 of the chain loops 40 and 41 extend parallel to and equi-distant from the vertical plane 100

defined by the axes of the sprockets 28 and 29, and 36 and 37.

Secured to the chains 40 and 41 is a bracket member 45 consisting of right-hand and left-hand upper bracket bars 46 and right-hand and left-hand lower bracket bars 47. The upper bracket bars 46 have bridge portions 48 which extend externally over the chains 40 and 41 so that the bracket bars 46 may be secured to the chains 40 and 41 by means 10 of pins 49, and the lower bracket bars 47 likewise have bridge portions 50 extending externally over the chains 40 and 41 so that the bracket bars 47 may be secured to the chains 40 and 41 by use of pins 51. The upper bridges 48 and the lower bridges 50 are spaced apart on the chains 40 and 41, and the bracket bars 47 extend convergently to engagement with a horizontally directed pin or bolt 53, this pin or bolt 53 extending 15 through the overlapping extended ends of the bracket bars 46 and 47, through the lower ends of vertical hanger straps 54, and through a central roller 55 which serves as a slide member within a slide or loop 56 in a sucker rod clamp member 57 which may be secured to the upper end of the polish rod 20. 20

As shown in Fig. 2, the chains 40 and 41 which constitute traveler members are each 25 guided by the respective upper and lower sprockets so as to form flattened vertical loops having side portions 42 and 43 and having substantially semi-circular end portions where the chains extend over the upper and 30 lower sprockets. The bracket 45 extends inwardly relative to the flat loop formed by the chain 40 a distance substantially equal to half the width of the loop, or in other words, half the distance between the vertical 35 portions 42 and 43 of the loop. From Fig. 40 it will be perceived that as the chains 40 and 41 move in a direction indicated by the arrow 58, the bracket 45 will be carried vertically downwardly, and the bolt 53 at the inner end of the bracket will travel through the vertical plane defined by the axes of the 45 upper and lower sprockets 28 and 29, 36 and 37. During this vertical movement of the 50 reciprocating parts, the roller 55 will rest substantially centrally within the laterally flattened loop 56, as shown in Figs. 2 and 4. When the bracket 45 reaches and is carried 55 around the lower sprockets 36 and 37, the roller 55 will be laterally offset for a short period of time, which will cause the roller to move laterally into an offset position in the loop 56, as indicated by dotted lines 60 of Fig. 4. A similar lateral displacement will occur 60 when the bracket 45 is carried around the upper sprockets 28 and 29. This lateral disalignment is due to the fact that the diagonal portions 61 of the upper and lower bracket arms 46 and 47 have a length which is greater than half the distance between the vertical 65 portions 42 and 43 of the chain loops. The

inward extension of the bracket 45 is the altitude of a triangle formed by the bracket bars 46 and 47 and the portion of chain extending between the bridges 48 and 50 thereof, whereas the bracket bars 46 and 47 represent the sloping legs of such triangle.

For the purpose of producing movement of the continuous traveling loop members formed by the chains 40 and 41, I place a drive shaft 63 parallel to the lower shafts 34 and 35, and from sprockets 64 keyed near the ends of the drive shaft 63 I extend chains 65 over larger sprockets 66 which are keyed on the outer ends of the shafts 34 and 35. On one end of the shaft 63, such as the leftwardly projecting end 67 thereof, a drive pulley or sheave 68 of relatively large diameter is mounted. The sprockets 64 are of the same size, as also are the sprockets 66, this resulting in a synchronous rotation of the shafts 34 and 35 and the inner sprockets 36 and 37 when power is applied to the drive shaft 63 through a rope or belt carried from a power source and over the pulley or sheave 68. 85

At the upper end of the frame 11 I mount cable sheaves 70 on a shaft 71 which extends between brackets 72. Over these sheaves 70 cables 73 are carried from hooks 74, attached to the upper ends of the members 54, to a counterweight 75 which slides in a guide member 76. The counterweight 75 is of sufficient weight to substantially counterbalance the weight of the moving parts of the pumping equipment, thus reducing to a minimum the power that must be transmitted through the chains 40 and 41. 90

To hold the sucker rods in substantially vertical alignment during the time the roller 55 is offset at the lower end of a pumping stroke, I provide guide rollers 78, as indicated in dotted lines in Figs. 2 and 4 and as shown in full lines in Fig. 1, these rollers being mounted at the upper end of an A-shaped supporting frame 79 which may be readily secured to the base 14 of the pumping equipment. The chain loops 40 and 41, as may be readily perceived from Figs. 1 and 2, are centralized on a single vertical plane which extends through the axes of the upper and lower sprockets, but these chain loops are also situated in separate vertical planes extending parallel to one another, with the result that the horizontal distance between the chains 40 and 41 is the same at every point. 105

In Figs. 1 to 4 of the drawings I have shown a means for compensating for the disalignment of the extended end of the bracket 45 at the end of a stroke, this compensating means including a member 57 secured to the upper extremity of the polish rod 20. In Fig. 5 I show a compensating device which may be placed in any desired position on a polish rod so that the reciprocating mechanism may be ready adjusted with respect to 115 120 125 130

the length of the sucker rods, polish rod, and the length of stroke of the pump. This compensating means also provides a guide for the sucker rods to prevent disalignment thereof when the reciprocating device is at the upper end of a power stroke. Accordingly, in Fig. 5 I show a polish rod 80 projecting through a clamp device 81 so that the upper end 82 thereof extends a distance above the device 81. The clamp 81 consists of a pair of cooperating parts 83 and 84 which are clamped on the polish rod 80 by means of bolts 85. In the parts 83 and 84 loops 86 and 87 are formed, these loops being horizontally flattened and equally spaced on opposite sides of the center line of the polish rod 80 so as to receive rollers 88 and 89 which are carried by a cross plate 90 by means of bearing members or pins 91. The center of the cross plate 90 is pivotally attached at 92 to the inwardly extending end of a bracket 93 carried by a chain 94, the parts 93 and 94 being respectively similar to the parts 45 and 40 shown in the preceding figures of the drawings. A guide tube or pipe 95 may extend from the clamp member 81 in vertically upward direction and in position surrounding the upper projecting end 82 of the polish rod 80. As shown to small scale at 96 in Fig. 5, the guide tube 95 extends between guide rollers 97 and is engaged by a hook 98 situated on the end of a cable 99 which extends to a counterweight 100. The clamp device 57 shown in Figs. 1 to 4 can be employed only on the upper end of a polish rod, such as indicated at 20, but a clamp of the character shown at 81 in Fig. 5 may be situated at any desired intermediate point of adjustment on a polish rod 80, thereby making it possible to readily adjust the long stroke reciprocating mechanism or pumping device relative to the sucker rod system of a pump so as to produce greatest efficiency in the operation of such pumping mechanism.

Although I have herein shown and described a simple and practical embodiment of my invention, it is recognized that certain parts or elements thereof are representative of other parts, elements, or mechanisms which may be employed in substantially the same way to accomplish substantially the same results; therefore, it is to be understood that the invention is not to be limited to the details disclosed herein but shall have the scope set forth in the following claim.

I claim as my invention:

A device of the character described, including: a pair of chain loops; an upper sprocket and a lower sprocket for each of said chain loops, said sprockets being so placed that said chain loops will travel through parallel vertical planes; means for causing travel of said chain loops over said sprockets; a bracket extending inwardly from adjacent portions of said chains, the inward extension

of said bracket being substantially one-half the diameter of said sprockets; a pump rod extending vertically from a pump; means engaging said pump rod, said means including a roller secured to the end portion of said bracket and a guide member secured to said rod, said guide member having a lateral slot receiving said roller; and guide rollers for preventing disalignment of said rod when said bracket is offset near an end of a vertical stroke.

In testimony whereof, I have hereunto set my hand at Coalinga, California, this 21st day of October, 1929.

JOHN S. HUNTER.
